RAIN LEGGINGS

Adelia D. M. Riedel, Los Angeles, Calif.

Application November 12, 1947, Serial No. 785,233

1 Claim. (Cl. 36—2)

1

My invention relates to articles of apparel, and particularly to a protective covering for the legs of a person. Specifically, the invention pertains to waterproof storm leggings and the like used to protect the legs of a wearer in inclement weather.

The waterproof leggings disclosed herein are designed particularly for use as a means for protecting women's stockings worn in the rain and snow and against splashing of water by passing vehicles. It is a primary object of my invention to provide leggings for the purpose specified which effectively cover and adequately protect the legs and the upper portion of the feet of the wearer, and another object is to provide leggings which are extremely light in weight and very economical to make so as to adapt them to be sold at an extremely low price.

Another object is to provide storm leggings which are adapted to be wrapped around the legs of the wearer and having fastening means, preferably in the form of either buttons and buttonholes or snap-fasteners for retaining the leggings on the legs of the wearer.

Another object is to provide leggings for use during inclement weather which include loops adapted to encircle the heels of the wearer's shoes and embodying elastic means at the upper ends of the leggings for drawing the same snugly around the legs.

A further object is to provide storm leggings which are adapted to be easily and quickly applied to and removed from the legs of the wearer and capable of being rolled or otherwise folded into a package of small compass so as to adapt them to be carried in a pocketbook or other receptacle when not in use.

Further objects will be apparent from the following description and from the drawing, which is intended for the purpose of illustration only, and in which:

Fig. 1 is a rear view, illustrating a pair of my improved storm leggings as applied to the legs of the person;

Fig. 2 is a side view of the ankle portion of one of the legs and a legging, as viewed in the direction of arrow 2 in Fig. 1;

Fig. 3 is a rear perspective view of one of the leggings;

Fig. 4 is a composite view of the two panels or sections of one of the leggings; and

Fig. 5 is a view similar to Fig. 2, showing the use of snap-fasteners for retaining the leggings in place on the leg.

Referring to the drawing in detail, my im-

2

proved legging 5 consists of a sheet of thin, flexible, waterproof material, such as oiled silk or plastic, preferably of a transparent nature although it may be tinted to harmonize with the color of the wearing apparel with which it is worn. While the sheet referred to above may consist of a greater or lesser number of parts, I prefer to construct the sheet from a pair of panels or sections 6 and 7, which are shown in detail in Fig. 4. As herein shown, the section 6, which is adapted to fit against the outer side of a leg 8 of a person, consists of a generally rectangular piece of the flexible material, the corners of the lower portion of the section being extended laterally to provide a point 9 at one side and a projecting tapered strap 10 at the other side thereof. The lower end of the section is made somewhat wider than its upper portion and it will be noted that the lower edge 11 of the section is curved slightly as indicated in Fig. 4. The material at the upper and lower ends 11 and 12 and along the vertical edge 14 of the section or panel 6 is folded or doubled back and hemmed by at least one row of stitches 13. Projecting from the apex of the strap 10 is an eye or buttonhole-loop 15 which may consist of a short length of elastic or inelastic cord, tape or the like having its ends sewed to the hem at the end of the strap. A similar eye or buttonhole-loop 16 is provided at the upper end of the section 6 and projects laterally from the hemmed vertical edge 14 thereof. Sewed to the hem at the bottom edge of the panel 6 are the ends of a larger elastic or inelastic loop 17 which is used for the purpose to be later explained. Above the loop 17, the section 6 may have a buttonhole 18 if desired.

The mating section or panel 7 is similar in shape to the section 6, having a pointed lower corner 20. The upper and lower edges of the section 7 are doubled back and hemmed by at least one row of stitches 21. Sewed to the hem at the lower edge of the section 7 are the ends of an elastic or inelastic loop 22 and stiched at spaced points to the hem at the upper edge thereof are the ends of an elastic strip 23. A button 24 is sewed to the panel 7 at a point adjacent one end of the elastic strip 23. Adjacent the lower edge of the panel 7 are similar buttons 25 and 26. Since it is desirable that the legging 5 follow closely the contour of the leg upon which it is worn, I prefer to form the legging by gradually reducing its size toward its lower end and this can be accomplished by slitting the material of the section 7 in an upward direction, and sewing the edges of the slit together as indicated at 27

in Fig. 4, this tapering seam being commonly termed a "dart."

The panels 6 and 7 can be made by conventional methods and with the use of forming and sewing equipment commonly employed in the fabrication of wearing apparel. To assemble the panels 6 and 7, it is only necessary to place their unhemmed vertical edges 28 and 29 together and sew them in this relationship, the loose edges being preferably arranged at the inside or reverse side of the leggings. It will be apparent that when the two panels 6 and 7 are sewed together in this manner, a single sheet is formed which is adapted to be wrapped around the leg of a person. It will also be noted that the pointed corners 9 and 20 of the panels 6 and 7 form together a gore 30 of substantially triangular shape adapted to overlie the instep portion of the wearer's foot or the upper portion of a shoe 31 worn by the person.

To apply the improved storm legging 5 to use it is placed in position against the front of the person's leg 8, with the gore 30 overlying the top of the wearer's shoe 31, after which it is wrapped around the leg with the vertical edge of the panel 6 overlapping the adjacent edge of the panel 7 as shown in Figs. 1 and 3. The upper portion of the legging 5 then encircles the calf of the leg and is retained in this position by merely inserting the button 24 through the buttonhole-loop 16. The combined length of the upper edges of the panels 6 and 7 is somewhat greater than the average girth of the calf portion of a leg so that normally a loose fitting of the legging around the calf would occur. However, the elastic strip 23 acts to pucker the material along the upper edge of the legging and thus draw the same snugly around the calf of the leg as shown in Fig. 1. With the legging 5 thus held up on the leg in the manner explained above, the tapered strap 10 of the panel 6 is brought around the back of the heel of the shoe 31 and the button 25 is received in its buttonhole-loop 15. At the same time, the button 26 may be passed through the buttonhole 18 when buttonholes are employed and a snug fit of the lower portion of the legging around the ankle is effected. Either prior to or following the fastening of the sides of the legging 5 around the leg 8, the loops 17 and 22 are looped or hooked around the heel of the shoe, as shown in Figs. 1 and 2, and thus the legging is held against upward movement on the leg.

When a pair of the leggings 5 is applied to a woman's legs, as shown in Fig. 1, the legs are adequately covered thereby and thus when expensive stockings are worn by the woman they are fully shielded from rain, snow and sleet and also protected against water splashed by passing vehicles. By overlapping the vertical edges of the legging to a substantial degree, the possibility of water or snow entering the legging is effectively avoided. It has been found that because the legging is form fitting, that is, conforms substantially to the shape of the leg on which it is worn, the need for extra fastening devices arranged intermediate the upper and lower ends of the legging is avoided and the application of the legging to the leg is greatly simplified. Moreover, since the legging is adequately held on the leg,

displacement of the legging during running, boarding vehicles, etc., is positively avoided. Furthermore, the improved storm legging is adapted for fabrication from light-weight, flexible transparent material so that the appearance of bulkiness is avoided and the stockings can be readily seen therethrough. The leggings are extremely light in weight and can be rolled or folded into a package of very small compass capable of being carried in a pocket or handbag. The improved legging is especially simple in construction and lends itself to mass production methods so that it can be manufactured and sold at a very low price. It will be apparent from the foregoing that the various buttonhole-loops can be made from elastic material, if desired, so that they will aid in drawing the legging snugly around the leg. Also, a pair of the buttons and buttonholes can be provided at the upper end of the legging to afford greater security. Referring to Fig. 5 of the drawing, it will also be noted that snap-fasteners 33 may be employed in lieu of the buttons shown in the preceding views within the concept of my invention.

While I have herein shown and described my improved storm legging as embodied in a preferred form and as applied to use in a particular manner, by way of example, it will be apparent that various modifications might be made therein without departing from the spirit of the invention. Consequently, I do not wish to be limited in this respect, but desire to be afforded the full scope of the appended claim.

I claim as my invention:

35 A rain legging for covering the leg and the instep portion of a shoe worn by a person, comprising: a sheet of flexible, waterproof material composed of two panels secured together in edge-to-edge relationship, the borders of said panels 40 being hemmed, said panels having pointed corners at the lower ends of their adjoining edges, said corners together providing a gore portion adapted to overlie the instep portion of the shoe, said sheet being of sufficient width to adapt it to 45 encircle the leg with one of its vertical edges overlapping its other vertical edge at the back of the leg; a pair of loops carried by said sheet and adapted to surround the shoe and engage the sole thereof forwardly of the heel; and buttons at the 50 upper and lower portions of one of said panels engageable in buttonholes in the other of said panels for releasably retaining said vertical edges in overlapping relationship.

ADELIA D. M. RIEDEL.
